UNITED STATES PATENT OFFICE.

JULIUS BRENZINGER, OF MOUNT VERNON, NEW YORK, ASSIGNOR TO
SANITARY CAN MACHINERY COMPANY, OF ELLSWORTH, MAINE, A
CORPORATION OF MAINE.

CAN-HEADING MACHINE.

No. 823,254.

Specification of Letters Patent.

Patented June 12, 1906.

Application filed June 15, 1905. Serial No. 266,408.

To all whom it may concern:

Be it known that I, JULIUS BRENZINGER, a citizen of the United States, residing at Mount Vernon, Westchester county, State of New York, have invented new and useful Improvements in Can-Heading Machines, of which the following is a specification.

This invention relates to a machine for securing can-heads to can-bodies of round, square, or other shape. This operation is performed by a seaming-roller, which is so guided as to accurately follow the contour of the can to be closed and to thus form a perfect joint.

In the accompanying drawings, Figure 1 is a side elevation of my improved can-heading machine; Fig. 2, a front view of the cam-shaft and adjoining parts; Fig. 3, a detail plan view, partly in section, of the seaming-levers 15 with some of the parts removed; Fig. 4, a side elevation thereof; Fig. 5, a vertical section on line 5 5, Fig. 3; Fig. 6, a cross-section through the guide-lever on line 6 6, Fig. 3; Fig. 7, a section on line 7 7, Fig. 6; Fig. 8, a 20 side view of the clutch and brake-operating cam and adjoining parts; and Fig. 9, a detail of part of the can-body, showing it engaged by the platform and chuck.

The letter A indicates the frame of the machine, and a is the power-shaft, which transmits motion by pulley a' and belt a² to a clutch-pulley b', loosely mounted upon a work-shaft b. To the latter is affixed a sprocket-wheel b², which transmits motion 25 by an endless chain c to a sprocket-wheel d', fast on a vertical worm-shaft d. Below sprocket-wheel d' there is mounted upon shaft d a second sprocket-wheel d², which transmits motion by chain e to a sprocket-wheel f'. This wheel is rotatably mounted 30 upon a vertically-movable rod f, which is in vertical alinement with shaft b. Chain c and sprocket-wheels b² d' correspond in size to chain e and sprocket-wheels f' d², so that 35 sprocket-wheels b² and f' will rotate with the same speed and their relative positions will always remain the same.

Sprocket-wheel f' forms part of a platform f², provided with a raised central section f³, which corresponds in shape to that of the can-body B to be headed and is adapted to enter a recess in the can-bottom B', Fig. 9. Rod f is guided in bearings A' A² of frame A

and may be raised and lowered, so as to bring the can-body into or out of engagement with the seaming means hereinafter described.

For operating rod f a hand-lever g, influenced by a spring g', is provided, which is connected by a link g² to a collar g³, loosely fitted upon the rod. Upon collar g³ are supported a pair of cushions g⁴, that bear against a collar f⁴, secured to rod f. By depressing handle g, rod f and platform f² will be raised, while upon releasing the handle the rod and 55 platform will be lowered by spring g'.

For seaming the can and operating the seaming means the following construction has been devised: Worm-shaft d is provided with a worm d³, engaging a worm-wheel h' of a cam-shaft h. This shaft is provided with a cam h² for operating the clutch and brake in manner hereinafter described and with a pair of cams h³ h⁴ for operating the seaming-levers. The drawings show two seaming-levers; but as their operating means are alike the same description will apply to both. Each cam h³ is engaged by a cam-roller i', journaled in a laterally-extending arm i of a sleeve i². The latter is vertically slidable 70 upon a spindle i, mounted in bearings A³ A⁴ and vertically adjustable by means of set-screws i⁴ i⁵. Spindle i serves as a pivot for an upper or guide lever j and a lower or seaming lever k, such levers having therefore coincident fulcrums. Guide-lever j is provided with a tubular hub j', secured to spindle i by a pin j². The lower threaded end j³ of hub j' carries a nut j⁴. To the free end of lever j is journaled a guide-roller j⁵, which travels in a 75 groove l' of a cam-disk l, fast on shaft b. The groove l' corresponds in form to that of the can to be headed. The lower section of disk l constitutes a chuck l', which is adapted to enter the recessed cover B² of can B, Fig. 9, and thus hold the can in position during the seaming operation. The free or front end of lever k carries the seaming-roller K, while its rear end is provided with a tubular hub k', which loosely surrounds hub j' of lever j. Hub k', and consequently lever k, is held 80 against vertical displacement by being confined between lever j and nut j⁴. Hub k' is provided with an outer longitudinal groove k', engaged by a vertically-movable wedge 85 k². The latter is adjustably secured by k³.

screws k^4 to a slide k^5 , also engaging groove k^2 and confined to the same by a cover k^6 . Slide k^5 is provided at its lower end with a roller k^7 , supported upon arm i^2 . Thus slide 5 k^5 and wedge k^3 will participate in the vertical reciprocating movement imparted to arm i^2 by cam h^8 . Wedge k^3 bears against a roller m' , journaled in the rear end of an auxiliary lever m , influenced by a spring m^2 and turning on a fulcrum n of guide-lever j . The front end of lever m is by a pivoted link o connected to the seaming-lever k .

In order to permit a proper adjustment of roller K , fulcrum n is made in the form of a screw which is adjustably secured to lever j 15 by tapping it eccentrically in a cylindrical plug n' . This plug is received by a pair of perforated lugs j^8 , projecting laterally from lever j . Intermediate the lugs j^8 plug n' is 20 embraced by a ring n' , carrying screw-bolt n^3 and nut n^4 . By loosening said nut plug n' is free to be turned, so as to adjust the position of plug n' , and consequently of screw n . After the adjustment has been effected nut n^4 is 25 again tightened.

By the construction described roller j^5 by 30 engaging groove l' swings the free end of lever j , as well as of lever k , to assume a position corresponding to the contour of the can-body. In addition to the movement thus 35 imparted to lever k the latter receives by wedge k^3 a further inward movement, whereby by the seaming-roller K is pressed against the can-body to perform the seaming operation.

35 Wedge k^3 is operated in the following manner: The rotation of cam h^8 will cause a vertical reciprocating movement of sleeve i^3 and its arm i^2 . When said arm is raised, it will lift roller k^7 and wedge k^3 . Wedge k^3 in rising will crowd roller m' , and consequently the 40 rear end of lever m , away from spindle i , so as to press the seaming-roller K against the can-body and cause the latter to perform the seaming operation. When arm i^2 is lowered, 45 wedge k^3 descends by gravity to permit spring m^2 to swing roller K off the can-body B . The cams h^8 h^3 are so set that the rollers K K are consecutively brought into engagement with the can to be headed. In this 50 way the first roller starts the seaming operation, while the second roller completes the same, as usual.

Hand-lever g , which serves to raise platform f^2 , also serves to start the machine and 55 to open the brake in the following manner: Lever g is provided with a depending arm g^5 , to which is pivoted one end of a rod p , the other end of which is connected to a lever r' , fast on a rock-shaft r , which is journaled in 60 frame A . To rock-shaft r is secured an elbow-lever r^2 , the lower arm of which is provided with a roller r^3 , engaging cam h^2 of shaft h . The upper arm of lever r is by rod s connected to a double lever t , pivoted at t' to 65 frame A . This lever engages a groove b^3 of

the movable member b^4 of clutch $b' b^4$, which may be of any suitable construction. The drawings show a friction-clutch provided with radially-movable jaws b^5 . These jaws are pressed against the inner surface of pulley b' by eccentrics b^6 and levers $b^7 b^8$ when clutch member b^4 is lowered. Lever t is by rod u further connected to a brake-lever v , pivoted at v' to frame A and influenced by a spring v^2 . Lever v engages the brake-shoe w' of a brake-disk w , fast on shaft b . It will be seen that by depressing hand-lever g roller r^3 will be lifted out of notch h^4 of cam h^2 . Further, the clutch member b^4 will be lowered to close clutch $b' b^4$, and thus start 70 the machine, while the brake $w w'$ is simultaneously opened by the engagement of stud v^3 of lever v with the tailpiece w^2 of brake-shoe w' . When the machine is started, roller r^3 will ride along the convex edge h^5 of cam h^2 , 75 and thus prevent the clutch from opening, even after hand-lever g has been released. After cam-shaft h has made a complete rotation roller r^3 will enter recess h^4 by the combined action of the springs $g' v^2$. In this way 80 lever r^2 will tilt levers g , t , and v to lower platform f^2 and open clutch $b' b^4$ and also to set the brake.

It will be seen that in my improved machine the guide-levers and seaming-levers 85 turn on coincident pivots and that the seaming-levers are further influenced by a vertically-movable wedge in such a manner that the seaming-rollers are forced against the can in a simple and efficient manner.

100 What I claim is—

1. In a can-heading machine, a guide-lever and a seaming-lever having coincident pivots, means for operating the guide-lever, and a vertically-slidable wedge adapted to operate 105 the seaming-lever, substantially as specified.

2. In a can-heading machine, a guide-lever and a seaming-lever having coincident pivots, means for operating the guide-lever, an auxiliary lever connected to the guide-lever and 110 the seaming-lever, and a wedge engaging the auxiliary lever, substantially as specified.

3. In a can-heading machine, a guide-lever and a seaming-lever having coincident pivots, means for operating the guide-lever, an auxiliary lever pivoted to the guide-lever, a link connecting the auxiliary lever to the seaming-lever, and a wedge engaging the auxiliary lever, substantially as specified.

4. In a can-heading machine, a guide-lever and a seaming-lever, said seaming-lever having a grooved hub, a vertically-movable wedge engaging said hub, an auxiliary lever engaged by the wedge, and means for pivotally connecting the auxiliary lever to the 125 guide-lever and the seaming-lever, substantially as specified.

5. A can-heading machine provided with a spindle, a guide-lever fast thereon, a seaming-lever having a grooved hub rotatable on 130

the spindle, a vertically-movable slide, a wedge connected thereto and engaging the grooved hub, an auxiliary lever engaged by the wedge, and means for pivotally connecting the auxiliary lever to the guide-lever and the seaming-lever, substantially as specified.

5 Signed by me at New York city, (Man-

hattan,) New York, this 14th day of June, 1905.

JULIUS BRENZINGER.
